UNITED STATES PATENT OFFICE.

ARTHUR NELSON SIMMONS, OF ASHTABULA, OHIO, ASSIGNOR OF ONE-HALF TO
W. EARLE MOORE, OF ASHTABULA, OHIO.

BROOM-HOLDER.

1,182,109.

Specification of Letters Patent.

Patented May 9, 1916.

Application filed April 28, 1915. Serial No. 24,524.

To all whom it may concern:

Be it known that I, ARTHUR NELSON SIMMONS, a citizen of the United States of America, and a resident of Ashtabula, Ashtabula county, and the State of Ohio, have invented certain new and useful Improvements in Broom-Holders, of which the following is a specification.

An object of the present invention is to provide a broom holder which may be easily and readily attached to a wall or other support and when attached it will suspend the broom from the wall whereby the broom straw will not come in contact with the wall which would cause the dirt and other foreign matter carried by the broom to deposit upon the wall.

Another object of the invention is to provide a device of this character which will be more efficient, strong and durable when in use and comparatively inexpensive in the cost of manufacture thereby rendering the same commercially desirable.

With the above and other objects in view the invention consists of the novel features of construction, combination and arrangement of parts as will be hereinafter more fully described and particularly pointed out in the appended claim.

In the accompanying drawings has been illustrated a simple and preferred form of the invention, it being, however, understood that no limitation is necessarily made to the precise structural details therein exhibited, but the right is reserved to any changes, alterations and modifications to which recourse may be had that come within the scope of the invention as claimed and without departing from the spirit or sacrificing the efficiency of the same.

The invention will be best understood by reference being had to the accompanying drawings taken in connection with the following detailed description forming part of the specification in which:

Figure 1, is a side elevation of the device as applied to a support and showing the position of the broom relative to the wall when supported thereby, Fig. 2, is an enlarged sectional view, and Fig. 3, is a plan view embodying the invention.

Reference now being had to the drawing wherein like and corresponding parts are designated by like reference characters throughout the several views, the numeral 1

represents a wall or other support to which is suspended a broom 2 by means of the improved broom holder. The broom holder comprises a plate 3 having its medial portion bent outwardly to form a loop 4. The upper extension 5 is provided with an aperture through which extends a screw or other fastening means 6 whereby the plate may be attached to the wall or other support. The arm plate 7 is provided with an opening 8 through which extends the loop 4 thereby forming a pivotable connection between the plate 3 and the arm 7. The opposite walls of the opening 8 are inclined and the upper end of the rear wall is provided with a biting edge 9 which is adapted to engage into the rear wall of the loop 4. The inner end of the arm 7 is rounded as at 10 to form a biting edge which will bite into the outer face of the wall. The outer or free end of the arm 7 is enlarged and provided with an opening 11 for the reception of the broom handle, but the diameter of this opening is of greater diameter than the exterior diameter of the broom handle for a purpose as will be later described. The walls of the opening 11 are inclined to form a gripping edge at the lower face of the plate arm which will bite into the broom handle for securing the broom to the holder.

By having the opening 11 of greater diameter than that of the broom handle the latter may easily be inserted through the opening when the arm 7 is substantially at right angles to the broom handle. When the broom handle is placed in proper position within the opening 11, the broom is allowed to drop by gravity until the arm 7 has assumed the position as shown in Figs. 1 and 2 where it extends outward and downward. When the arm 7 is in this position the biting edge formed by the opening 11 will grip the broom handle and the edges 10 and 9 will bite into the support and hook 4 respectively thereby locking the arm in position, whereby the broom will extend parallel to the support and in spaced relation thereto which will prevent the broom straw from rubbing against the wall and depositing dirt carried by the broom straw.

In Figs. 2 and 3 the device is shown as attached to a block 12 which may be fastened in any suitable manner to the wall or other support. The block is rectangular in configuration so that when it is desired the arm 110

7 may be permanently attached to the broom handle in any suitable manner and by swinging the plate 3 to one side of the block the arm may be severed from the plate 3. From Fig. 2 it will be seen that the plate 3 is only attached at its upper end by the screw 6 to the support thereby permitting the plate to swing upon the pivoted connection.

Having fully described the invention what I claim as new and desire to secure by Letters Patent is:—

The combination with a support, a plate, means for pivotally connecting one end of

the plate to the support, a loop formed with in the plate, a broom supporting arm pivotally connected to said loop, biting edges formed upon said arm and adapted to engage said loop and support for retaining the arm in locked position.

In witness whereof, I hereunto subscribe my name to his specification in the presence of two witnesses.

ARTHUR NELSON SIMMONS.
